UNITED STATES PATENT OFFICE.

MICHAEL J. DOUGHERTY, OF CARBONDALE, PENNSYLVANIA.

CAR-COUPING.

SPECIFICATION forming part of Letters Patent No. 240,238, dated April 19, 1881.

Application filed September 4, 1880. (Model.)

To all whom it may concern:

Be it known that I, MICHAEL J. DOUGHERTY, of Carbondale, in the county of Lackawanna and State of Pennsylvania, have invented a new and useful Improvement in Car-Couplings, of which the following is a specification.

Figure 1 is a sectional side elevation taken through the line *xx*, Fig. 2. Fig. 3 is a plan view. Fig. 4 is a perspective view of the coupling-pin.

The object of this invention is to furnish car-couplings so constructed that cars of the same height and of different heights can be coupled automatically as the cars are run together.

Similar letters of reference indicate corresponding parts.

A represents the bumper-heads, the mouths of which are made hopper-shaped in the ordinary manner, to guide the coupling-link B into place as the cars are run together. The upper and lower sides, C, of the cavities of the bumper-heads A are inclined or curved, as shown in Fig. 1, to guide the coupling-link B into place when coupling cars of different heights.

D are the coupling-pins, which pass down through holes in the bumper-heads A near their forward ends. Upon the upper ends of the coupling-pins D are formed cross-heads E, the arms of which rest in grooves in the upper sides of the bumper-heads A, so that the lower ends of the said coupling-pins D can swing inward to allow the entering-links C to push the lower ends of the said coupling-pins D back and pass them when the cars are run together.

Upon the upper end of the coupling-pin D is formed a short upwardly-projecting point or arm, F, to serve as a handle, for convenience in withdrawing the said coupling-pin to uncouple the cars. The inner surfaces of the upper and lower sides of the cavity of each bumper-head A are grooved in the rear of the coupling-pin D, to allow the lower end of the said coupling-pin to swing back, so that the end of the coupling-link B can push back

and pass the end of the said coupling-pin D when the cars are run together, as shown in Fig. 1.

G is a pin which is inserted in a hole in the rear of the coupling-pin D in each bumper-head A. In the forward side of each pin G are formed three notches, H, to receive the end of the coupling-link B, and support the outer end of the said link in position to enter the bumper-head of an adjacent car when the cars are run together. The middle notch of the pin G is used when the adjacent cars are of the same height. The lower notch is used when a lower car is to be coupled with a higher car, and the upper notch when a higher car is to be coupled with a lower car. The pin G has a collar or shoulder, I, formed upon it, to rest upon the top of the bumper-head A and thus support the said pin in place.

To the upper end of each of the holding-pins G is attached the end of a short chain, J, the other end of which is attached to the bumper-head A, to prevent the said pins G from being lost when withdrawn from the said bumper-heads A.

The pin G of the car to be coupled with the car carrying the coupling-link B must be withdrawn when the cars are to be coupled, to allow the coupling-pin D to be pushed back by the entering-link B. When the cars are coupled one or both the holding-pins G must be withdrawn to give the link B the necessary play.

Having thus fully described my invention, I claim as new and desire to secure by Letters Patent—

1. A coupling-pin for cars having the body D, arms E E, and projection F, as shown and described.

2. In a car-coupling, the pin G, having three notches, H, adapted to receive the end of link, whether the opposite draw-head is higher, lower, or of the same height, as specified.

MICHAEL JOSEPH DOUGHERTY.
